US0D1019681S

(12) **United States Design Patent** (10) Patent No.: **US D1,019,681 S**
(45) Date of Patent: ** Mar. 26, 2024

(54) **DISPLAY SCREEN OR PORTION THEREOF WITH GRAPHICAL USER INTERFACE**

(71) Applicant: **TRUIST BANK**, Charlotte, NC (US)

(72) Inventors: **Candice Roberts**, Wake Forest, NC (US); **Alisha Belk**, Raleigh, NC (US); **Elizabeth Hammond**, Durham, NC (US); **Lee Ratcliffe**, Garner, NC (US)

(73) Assignee: **Truist Bank**, Charlotte, NC (US)

(**) Term: **15 Years**

(21) Appl. No.: **29/827,749**

(22) Filed: **Feb. 22, 2022**

Related U.S. Application Data

(62) Division of application No. 29/666,957, filed on Oct. 17, 2018, now Pat. No. Des. 947,207, which is a division of application No. 29/555,075, filed on Feb. 18, 2016, now Pat. No. Des. 835,117.

(57) CLAIM

The ornamental design for display screen or portion thereof with graphical user interface, as shown and described.

DESCRIPTION

The FIGURE is a front view of a display screen or portion thereof with graphical user interface showing our design. The outermost broken lines illustrate a display screen or portion thereof and form no part of the claimed design. The remaining broken lines illustrate the graphical user interface and form no part of the claimed design. The stippling represents a contrast in appearance and forms part of the claimed design.
